UNITED STATES PATENT OFFICE

LOUIS E. OGLIN, OF DES MOINES, IOWA

DESIGN FOR A LAMP SHADE

Application filed July 29, 1931. Serial No. 40,707. Term of patent 7 years.

To all whom it may concern:

Be it known that I, LOUIS E. OGLIN, a citizen of the United States, residing at Des Moines, in the county of Polk and State of Iowa, have invented a new, original, and ornamental Design for a Lamp Shade of which the following is a specification, reference being had to the accompanying drawings, forming part thereof.

Figure I shows a perspective view of a lamp shade embodying my new design.

Figure II shows a side elevation thereof, and

Figure III shows an end elevation.

I claim:

The ornamental design for a lamp shade as shown.

LOUIS E. OGLIN.
